UNITED STATES PATENT OFFICE.

ABRAHAM L. ELIASOFF, OF NEW YORK, N. Y.

FINGER RING.

Application filed September 11, 1925. Serial No. 55,660.

The present invention has for its particular objects; the provision of an improved finger ring having relatively movable sections whereby the ornamental design of the ring may be varied at will; the provision of a finger ring having means to vary the arrangement of jewel mountings disposed on the ring; the provision of a finger ring having relatively movable sections provided with means for retaining the sections against accidental movement; and generally to provide a novel and improved finger ring construction.

15 Drawings.

Figure 1 is a fragmentary section through a finger ring constructed in accordance with the principles of the invention;

Figure 2 is a section therethrough on the line 2—2 of Figure 1;

Figure 3 is a plan view of a portion of the ring shown in Figure 1;

Figure 4 is a fragmentary plan view of a modified form of finger ring.

25 Description.

In detail the invention comprises a flat band ring 10 of gold or other suitable precious metal having integrally formed thereon at one edge an upstanding annular flange 11 disposed at a right angle to the band 10. Rigidly secured to the band 10 at the opposite side edge is a ring section 12 having a series of spaced jewels 13 mounted in its periphery, which periphery may be provided with any suitable ornamentation.

The jewel carrying ring section 12 is preferably substantially square in cross section with its inner edge 14 terminating substantially midway between the flange 11 and the opposite side edge of the ring band 10. In the channel thus formed between the flange 11 and the ring section 12 a movable ring section 15 is mounted in such manner that it may be rotated over the band 10. The movable section 15 is also provided with jewels 16 in the outer face thereof, which may also be provided with suitable ornamentation.

The movable ring section 15 is also preferably square in cross section filling the channel between the flange 11 and station-

ary section 12. The meeting faces of the sections 12 and 15 are milled to provide fine coarse serrations 17 for interengagement normally to hold the removable ring section 15 against rotation.

As illustrated in Figure 3 the ring sections are shown disposed in a fixed relation of the jewels carried by the sections whereby to provide a certain design. It is apparent that upon rotation of the ring section 15 the jewels 16 may be varied relative to the jewel 13 whereby a different design is produced. The peripheral faces of the ring sections terminate flush with the edge 18 of the flange 11 providing a neat compact ring construction wherein the design of the ring may be varied to suit the taste of a wearer.

In the modified form illustrated in Figure 4 the band 10 has secured to its edge opposite the flange 11 a stationary ring section *c* between which and the flange 11 are disposed a plurality of movable ring sections *a* and *b*. In this form of the invention each of the ring sections *a*, *b*, and *c* has secured to the periphery thereof a jeweled bar mount which extends transversely across all three ring sections. The stationary ring section *c* has the intermediate bar mount 2 rigidly secured thereon and extending over the ring sections *a* and *b* which rotate therebeneath over the band 10. The upper mount 1 is secured to the ring section *a* while the bar mount 3 is secured to the ring section *b*, whereby the mounts 1 and 3 may be rotated around the ring for movement relative to the center mount 2, whereby a varied design or grouping of the jewel mountings may be secured at will.

80 Claims.

1. A finger ring comprising a finger band, an upstanding flange formed on one edge thereof and integral therewith, a stationary annular ring section rigidly secured to the periphery of said band adjacent the opposite side edge thereof, a movable annular ring section rotatably mounted over said band between said flange and stationary ring section with the peripheries of said sections and flange being flush, and interengaging

means on the opposed meeting faces of said sections for retaining said movable section in adjusted position.

2. A finger ring comprising a flat annular finger band having an upstanding flange formed at one edge thereof and integral therewith, a stationary annular ring section rigidly secured on said band at the opposite edge thereof and extending across half the

width of said band, and a movable annular ring section rotatable over said band between said stationary section and flange, one of said sections having a serrated side face for engaging the adjacent face of the other of said sections for retaining said movable section in adjusted position.

ABRAHAM L. ELIASOFF.
